Patented Apr. 15, 1969

213,846

RUG SHAMPOOER

Jerrold L. Kingsley, San Francisco, Calif., assignor to American Home Products Corporation, New York,
N.Y., a corporation of Delaware

Filed Dec. 14, 1967, Ser. No. 9,773

Term of patent 14 years

Int. Cl. D7—06

U.S. Cl. D49—14

FIG. 1

FIG. 2

I claim:

The ornamental design for a rug shampooer, substantially as shown and described.
